UNITED STATES PATENT OFFICE.

SAMUEL B. WATERS, OF JOHNSTOWN, PENNSYLVANIA.

COMBUSTION DEVICE.

Application filed May 21, 1921. Serial No. 471,494.

To all whom it may concern:

Be it known that I, SAMUEL B. WATERS, a citizen of the United States, residing at Johnstown, in the county of Cambria and 5 State of Pennsylvania, have invented a new and useful Improvement in Combustion Devices, of which the following is a full, clear, and exact description:

My invention relates to a combustion device and particularly to a type of such device as applied to boilers wherein the gases generated in the fire-box are subjected to efficient combustion in a combustion chamber.

15 An object of my invention is the provision of such a device wherein the combustion is sufficiently complete to eliminate smoke.

Another object of my invention is the provision of such a device wherein the combustion is so complete as to materially increase the efficiency of the heat-producing fuel.

A further object of my invention is the provision of such a device wherein an intermediate wall is arranged to heat and conduct air or other oxygen-containing gas into contact with the combustible gases produced in the fire box.

30 A further object of my invention is the provision of such a device wherein the wall is composed of refractory material in the form of blocks or units having when assembled checkered passages through which the air is conducted from the ash pit and heated 35 before mixing with the combustible gases.

Many other objects and advantages of my invention will be apparent to those versed in this art.

40 My invention will be better understood by reading the following description and the accompanying illustrative drawings showing an apparatus embodying the principles of my invention and in which:

Figure 1 is a side view of a boiler partly 45 in section with my invention applied thereto;

Figure 2 is a section in line II—II of Figure 1 looking in the direction of the arrows;

Figure 3 is a perspective view of one of 50 the refractory blocks or elements constituting the body of the wall; and

Figure 4 is a perspective view of the refractory blocks or elements which are placed on the top of the wall.

55 Referring to the drawings, the boiler 1

may be of any desired type or construction, such as a sectional boiler as shown.

The sections are provided with feed or circulation pipes 2 in the usual manner for supplying and providing circulation for 60 the water which is customarily used in such boilers.

The boiler is provided with fire box 3 having a generating chamber and a secondary combustion chamber 4. Between the fire box 65 and combustion chamber is a refractory wall 5. This wall is built up of refractory blocks 6 of the type shown in Figure 3. These blocks may be of any suitable refractory material or heat resisting metal, such as cast 70 iron. Each of these blocks has side members 7 and 8 and intermediate members 9. The members 9 are set apart to provide a space 10 and the ends of the members 7 and 8 extend outwardly beyond the adjacent 75 members 9, so that when two of the blocks 6 are set end to end a space 10 is provided between the blocks. The side members 7 and 8 also extend above and below the upper and lower edges of the members 9 so that 80 when two blocks 6 are set one upon another a space 11 (Figure 1) is provided which communicates with each of the spaces 10 throughout the width of the wall. These 85 spaces 11 may be termed headers or manifolds. The blocks 6, as shown in Figure 2, are staggered relatively to each other according to the usual custom of laying bricks. This arrangement is provided for the purpose of giving strength to the wall. 90

The wall 5 is built up according to the type of the boiler to separate the generating chamber from the secondary combustion chamber, except through the opening 12. The wall 5 at the lower part of the opening 95 12 is capped off or provided with refractory blocks preferably of the type shown in Figure 4. These blocks 6^a are substantially the same in construction as that shown in Figure 3, except one side is chamfered off. These blocks as shown in Figure 1 are placed with the chamfered edge or side toward the secondary combustion chamber.

The wall 5 is carried by a wall support 13 which is placed in a position similar to the grate bars 14. This wall support is provided with openings to permit air to pass through the plate into the wall 5 and through the wall into the combustion chamber.

105 The combustion chamber is separated from 110

the ash pit by a division plate 15 and is otherwise reasonably air tight.

The boiler is provided with the usual exit 16 for waste gases.

5 If it is desired to apply my invention to a boiler already in use, one or two of the grate bars may be removed and the wall support placed in position and the wall built thereon and taking the form substantially 10 as shown in the drawings.

In operation the boiler is filled to the proper level with water and the fire is started in the fire box. The fire produces a considerable amount of heat due to the usual 15 combustion therein. The combustion in the fire box or generating chamber, however, is not complete. The gases produced therein pass over the wall 5 into the secondary combustion chamber 4. As they pass over the

20 top of the wall the air or other oxygen containing gas which comes through the ash pit into and through the wall 5, issues from the top of the wall and mixes with those gases in proportions having been predetermined so as to effect a complete combustion in the chamber 4. The wall 5, after the boiler is in operation for a short while, becomes heated so that the air which issues from the top of the wall is heated to a sub-

30 stantial temperature, with the result that the combustible gases are not materially chilled as they enter the chamber 4. After the gases are efficiently and completely burned in the chamber 4 the waste gases pass from 35 the boiler through the exit connection 16.

The boiler is provided with the usual doors and dampers and cooperating mechanism which are so well known that they need no description. In fact such devices are 40 different in different types of boilers.

My invention has many advantages. It is

simple and easily applied not only to new boilers wherein provision is made for its application in the manufacture of the boiler, but also to boilers not having my invention 45 therein when originally built; there are no moving parts and therefore nothing to require adjustment or repair as a result of which the maintenance and upkeep expense is insignificant; a substantial economy is effected in the fuel combustion in that the gases produced in the generating chamber are completely consumed; the air used to effect the complete combustion is heated to the proper temperature before being mixed 50 with the combustible gases which materially aids in the efficient operation of the device.

Many other advantages will appear to those skilled in the art.

I have illustrated and described one type 60 of boiler with my invention applied thereto, but I desire it to be understood that the boiler shown in the drawings is merely illustrative and I am not to be limited in any manner to any particular type of boiler as 65 my invention has wide application to boilers of any type and therefore I am not to be limited except by the claim attached hereto.

I claim:

The combination in a boiler of a fire box, 70 a bridge wall placed in the fire box, said bridge wall being constructed by sections of refractory material having vertical and horizontal passages therein, such passages extending throughout the width and height of 75 said wall and used for conducting air into the fire box where it is mixed with the gases in the combustion chamber, substantially as described.

In testimony whereof, I have hereunto set 80 my hand.

SAMUEL B. WATERS.
